UNITED STATES PATENT OFFICE.

ERNEST ARTHUR HAILWOOD, OF MORLEY, NEAR LEEDS, ENGLAND.

APPARATUS FOR IGNITING MINERS' LAMPS.

1,030,297.

Specification of Letters Patent. Patented June 25, 1912.

Application filed December 8, 1908. Serial No. 466,520.

To all whom it may concern:

Be it known that I, ERNEST ARTHUR HAILWOOD, a subject of the King of Great Britain and Ireland, whose postal address is 7 Gladstone Terrace, Morley, near Leeds, in the county of York, England, have invented certain new and useful Improvements in Apparatus for Igniting Miners' Lamps, of which the following is a specification.

10 This invention relates to improvements in apparatus for igniting miners' safety lamps of the class in which a self contained friction igniting device is used in the lamp, and has for its object the construction and arrangement of such an apparatus so that same cannot readily be tampered with, and which is so arranged that a lamp placed in the apparatus may only be ignited after the lamp or light admission opening in the lamp 20 or chamber has been completely closed, and rendered flame proof, thus should an attempt be made to ignite a defective lamp in dangerous surroundings, such attempt will not be attended with danger, as would 25 be the case could the device be operated while the lamp was exposed to the outer air.

In describing my invention in detail, reference is made to the accompanying sheets of drawings, similar letters generally indicating similar parts, in which,

Figure 1 represents a sectional elevation of one form of apparatus. Fig. 2 represents a similar view of another form. Fig. 3 represents a sectional plan of the apparatus 35 shown in Fig. 2. Fig. 4 represents an elevation of another form. Fig. 5 represents an irregular cross section through the device shown in Fig. 4. Fig. 6 is a sectional view of a further modification. Fig. 7 is an elevation of another modification. Fig. 8 is a sectional view of means for securing the lamp in the case. Fig. 9 is a horizontal section through Fig. 8. Fig. 10 is a vertical section of another form for securing the 45 lamp in position. Fig. 11 is a vertical section of means for raising and operating the igniter, and Fig. 12 represents a sectional view of the complete apparatus.

In carrying out my invention, Fig. 1 shows a lamp L placed eccentrically in a stationary cylindrical inner chamber A, provided at its base with an aperture D for the admission of an operating device C, such device C, being mounted in the lower portion 55 of the revoluble outer chamber B. The lamp L may be clamped in position by

means of a hinged device or clamp such as E. The operating device C, by preference, comprises a handle, free to be operated for its purpose only when the chamber B is securely closed on the chamber A, so that the lamp admission opening A¹ is completely covered in. The said handle is contained in the form of a shaft C¹ provided with a flange C², and in a recess C³ is mounted a spring C⁴, the upper end of shaft C¹ terminates in a screw thread, claw, or the like C⁵ for engaging the usual friction igniter in the lamp base. As will be seen, when the chamber B is in the open position, 60 the screw C⁵ or the like will abut against the underside of the blank walls of chamber A. As the chamber B is revolved, the device C is brought nearer to the aperture D, and when the admission opening A¹ is finally 65 closed, the device C after being pressed upward by its spring, may be screwed into the igniter in the lamp and operated up and down, and thus cause, by friction, a cap or the like to be exploded, or ignited in the 70 lamp, and the lamp wick or cotton ignited. The chamber A may have its lamp admission aperture A¹ guarded by a semi-circular door A², and as the chamber B is revolved around the chamber A, such door will be automatically closed, and may be hinged at 75 either the side or top. This construction may be seen in Fig. 3. In place of the spring C⁴ a cam path or rack may be arranged below on the movable door or chamber and in connection with the device C⁶, and which latter will at a given moment travel in such a manner as to be pressed 80 upward into aperture D, and engage with and automatically operate the lamp igniting device, the device C⁶ disengaging the lamp on the re-opening of the chamber. A method of carrying this into effect is shown 85 in Fig. 11, device C⁶ carried by chamber A having a deep pinion P attached about its 90 middle and a roller P¹ on a carrier P² loosely pivoted toward its lower extremity. The latter roller runs in a cam path P³ in 95 such a manner as to remain in the low position until the lamp admission openings have 100 completely closed, about which time the sloping portion P⁴ of the cam path will operate against the roller P¹ causing same together with part C⁶ to rise, and during 105 this rising the latter is caused to rotate owing to the rack P⁵ carried by the moving portion B engaging the pinion P; de-

vice C⁶ would therefore enter and engage with the igniting device in the lamp. The continued movement of the chambers will automatically cause the roller P¹ and device 5 C⁶ to fall and rise according to the number of serrations in the cam path. The reversal of the direction of operation of the chambers would cause the rack to finally lower pinion P and the device C⁶ and roller P¹, or if the 10 movement is continued in a forward direction I may place a similar short rack in a convenient position so as to cause the pinion, etc., to lower.

Fig. 2 shows a form of device where the 15 lamp L is placed in a revoluble cylindrical chamber A³, the chamber B² being stationary, the chamber A² being revolved by handle H working in a semi-circular slot H¹ in chamber B², or in any other convenient 20 manner. The relationship between the aperture D and device C will be understood from the drawing, the before mentioned semi-circular door A² is shown in elevation in Fig. 2 and in plan in Fig. 3.

25 Figs. 4 and 5 show a form of device where the lamp L is placed in a rectangular chamber A⁴ provided with a flat or semi-circular sliding outer chamber or door B³, having an under flange B⁵ which carries an operating device C⁷, and in the chamber A⁴ in the lamp ring L¹ or base of the said chamber is formed an aperture D through which the device C⁷ may pass only when the door B³ is closed. The door B³ may be arranged to 30 operate in guides formed inside the chamber A⁴, and the opening A¹ may be guarded by an additional door, if desired. The lamp L may be clamped in the chamber A⁴, as before described, or may rest in its ring and 35 40 the upper portion of the lamp be retained in a clip F, which, with the gripped lamp, may be pulled upward by handles F¹, and operated against the device C⁷, when the latter is in position in the lamp. The construction 45 of this clip will be understood from the drawings. In some cases, igniting devices of the friction class are operated from the side, in which event the device C⁷ may be placed in a suitable position, and the moving 50 door or chamber will be provided with an aperture through which the device C⁷ may pass only when the door is closed.

Fig. 6 shows a form of apparatus in which a lamp L is provided with a friction igniting device, having a plain iron or iron 55 guarded head and which may be operated by means of a magnet, preferably electro. The before mentioned extra door guards may be used in this case, though a simple revolving 60 inner and stationary outer chamber is shown, the apertures D, D¹, only coinciding when the chamber door is closed. The chambers may, however, be in any of the other suitable herein described forms. In 65 the figure the chamber A⁵ is rotated by a

side handle H working in slot H¹ in chamber B⁶. The lamp L may be clamped in its chamber or retained in position by a stiff spring plunger P, of any ordinary construction. The chamber B⁶ is mounted on a chamber T carrying the electromagnet M and battery M¹ or the like, and in the base of chamber A⁵ is formed one terminal J, and in the base of chamber B⁶ is formed another terminal J¹, such terminals being brought together on the closing of the chambers to close a circuit. In place of the terminals a stop on the moving chamber or door may operate and close a push or switch in the position of terminal J¹. The magnet rod M² 70 will have a plain head for magnetically gripping the friction device in the lamp. The other end of the said rod will terminate in a flange M³ and the rod will be embraced by a sliding ring N carried on a shaft N¹ pivoted to a lever N² passing through the chamber T, the lever N² carrying a sliding guard N⁴ for protecting the opening or slot N⁵, a spring N⁶ keeping the magnet bobbin in the up position. On the rod or 75 shaft N¹ is carried a terminal J² connected to the electromagnet coil, and on a suitable rest J³ below same is a guarded terminal J⁴ connected to the battery or like M¹, the other terminal of said battery being connected to 80 the push or terminal J¹ and thence by contact with terminal J to the magnet coil one end of which is connected to the metallic frame. Terminal J is also connected to the metallic frame of the device. The chamber A⁵ is revolved until the apertures D and D¹ coincide when the head of magnet rod M² 85 will spring through and enter a recess in the lamp igniting device and come in contact with the iron head or a spring depressed guard in connection with such igniting device. The lever N² is then depressed down when terminals J² and J⁴ will meet and switch current through the magnet bobbin exciting same, and causing the head M² to 90 magnetically seize hold of the lamp igniting device. The continued movement of lever N² will cause the lamp igniter to be completely operated, and the lamp ignited, and 95 this with perfect safety. 100 105 110 115

In another form, Fig. 7, a lamp may be placed in a square or rectangular chamber provided with a door or moving chamber A⁶ in the form of a quadrant B⁴ and the lamp may be carried in such quadrant. The base 120 of such quadrant will be in the form of a guard plate or flange provided with aperture D, and on the base of chamber B will be carried the device C. As the door is closed, the aperture D and device C will be 125 coincident, and the lamp may be ignited.

A locking device such as G, Fig. 1, may be attached to the apparatus, such device comprising a lock recess or like G¹ in one chamber wall or portion thereof for the re- 130

ception of a spring lock bolt G, contained in the other chamber, such device being arranged to lock the apparatus in either the open or closed position, or both, the bolt 5 being withdrawn when desired by the person in charge, by means of a special key, such as a hollow spindle having a left hand thread, the bolt end G being suitably threaded or otherwise, as is convenient. In 10 place of the lamp being clamped in position in its chamber, and held therein by a spring plunger, the lamp base ring L¹ may be provided with what is known as a bayonet joint, the lamp being provided on its base 15 with one or more projections K which may pass into vertical recesses K¹ in the lamp ring L¹, and pressed down therein, and such recesses K¹ will communicate with horizontal ones K², the lamp being given a slight 20 turn to place same in position, Figs. 8 and 9. In a further form of clamping device, the chamber A may be provided with semi-circular clips L² carried by angle levers L³ pivoted in the said chamber walls, such 25 levers project through the sides of chamber A into cam paths L⁴ in walls of chamber B. As the chamber B is turned, the levers would be pressed in and thus cause the semi-circular clips to grip the lamp, Fig. 10. 30 It will be obvious that by forming the apparatus of thin sheet metal, same may be permanently attached to the lamp, rays of light being normally cast through what has been herein described as the lamp admission 35 door. The moving portion may be operated vertically instead of horizontally.

What I claim as my invention is:—

1. In apparatus for igniting miners' lamps, each having an opening and provided with a frictional igniter, the combination of a casing inclosing the lamp and provided with a doorway for inserting the lamp, said casing having an opening registering with the opening in the lamp, means 45 for closing the doorway, and means registering with the opening in the casing when the doorway is closed for operating the frictional igniter.

2. An apparatus for igniting miners' 50 safety lamps provided with frictional igniters, comprising a casing adapted to receive the lamp, a second casing surrounding the first casing, both of the casings having openings therein through which the lamp may 55 pass and one of said casings being movable in relation to the other, said casings also having openings therein, registering with

each other when the lamp chamber is closed, and means passing through said last-mentioned openings when the lamp chamber is 60 closed for operating the frictional igniter.

3. An apparatus for igniting miners' lamps provided with frictional igniters, comprising a casing having an opening therein for the introduction of the lamp and an opening registering with the igniter, a surrounding casing also having like openings therein, one of said casings being movable in relation to the other, and the second mentioned openings registering only when 70 the casings are closed, means adapted to be passed through said registering openings for operating the frictional igniter, and locking means for the casings.

4. An apparatus for igniting miners' 75 lamps provided with frictional igniters, comprising a casing, means therein for holding the lamp, said casing having an opening therein through which the lamp is introduced, a second casing surrounding the 80 lamp casing, one of said casings being movable in relation to the other to close the lamp casing, and means for operatively engaging the frictional igniter only when the lamp casing is closed.

5. An apparatus for igniting miners' 85 lamps provided with frictional igniters, comprising a casing having an opening therein through which the lamp is introduced, a second casing surrounding said 90 first named casing, means for moving one of said casings in relation to the other for closing said opening, said casings having igniting openings therein, registering with each other when the first named opening is closed, 95 whereby access can be had to the igniter, an electro-magnet M, a magnet rod passing through the same, and adapted to pass through the igniting openings in the casings 100 to engage with the igniter in the lamp, contacts brought into engagement when the first named opening in the lamp casing is closed, a source of electric current connected with one of said contacts, and means for moving the magnet rod and for connecting the source of current with the electro-magnet.

In witness whereof, I have hereunto set my hand, in the presence of two witnesses.

ERNEST ARTHUR HAILWOOD.
